The ornamental design for a patient support cart, as shown and described.

DESCRIPTION

FIG. 1 is a front perspective view of a patient support cart showing our new design;

FIG. 2 is a top plan view thereof;

FIG. 3 is a bottom plan view thereof;

FIG. 4 is a right elevation view thereof;

FIG. 5 is a front elevation view thereof;

FIG. 6 is a left elevation view thereof; and,

FIG. 7 is a rear elevation view thereof.

The dashed lines shown in the figures represent environment and forms no part of the claimed design.
